CLAIM

The ornamental design for laundry basket, as shown and described.

DESCRIPTION

FIG. 1 is a front, left and top perspective view of laundry basket, showing my new design;
FIG. 2 is a rear, right and top perspective view thereof;
FIG. 3 is a rear, right and bottom perspective view thereof;
FIG. 4 is a front view thereof;
FIG. 5 is a rear view thereof;
FIG. 6 is a left side view thereof;
FIG. 7 is a right side view thereof;
FIG. 8 is a top plan view thereof;
FIG. 9 is a bottom plan view thereof; and,
FIG. 10 is an enlarged view of portion of FIG. 1 thereof. The broken lines shown in the drawings illustrate portions of the laundry basket that form no part of the claimed design. The dash-dot lines illustrate the boundary of the enlarged views and form no part of the claimed design.

1 Claim, 10 Drawing Sheets(56)
